UNITED STATES PATENT OFFICE.

CHARLES COOK, OF WINSTED, CONNECTICUT.

VEHICLE-AXLE.

SPECIFICATION forming part of Letters Patent No. 254,466, dated March 7, 1882.

Application filed November 12, 1881. (No model.)

To all whom it may concern:

Be it known that I, CHARLES COOK, of Winsted, in the county of Litchfield and State of Connecticut, have invented certain new and useful Improvements in Axles; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to carriage or wagon axles, and its object is to provide a more efficient mechanism for keeping the sand out of the rear end of the axle-box than has heretofore been in use.

In the accompanying drawings, illustrating my invention, Figure 1 shows a cross-section through the axle-box, with the axle represented in full within it. Fig. 2 shows a cross-section through Fig. 1 on the line *x y*.

A represents the axle.

25 B is the axle-box.

C is the nut for holding on the wheel.

D is the flange at the rear of the spindle of the axle for receiving the inward thrust of the wheel. Back of this there has heretofore been 30 in use a second flange, with an intervening space or groove to form a sand-box, which has been covered by the rear end of the axle-box, so as to form an inclosed space. Upon this construction my present invention is an improvement.

35 E is the rear flange of the axle, coming nearly or quite flush with the rear end of the axle-box

B, and forming part of that portion of the axle back of the spindle. Its outer circumference is intended to fit as closely into the axle-box 40 as possible without touching, so as to prevent the entrance of sand and dirt as far as practicable.

Between D and E there has heretofore been a single groove. In my improved axle I insert 45 another flange, F, so as to divide the space into two parts. The outer groove, G, serves as the sand-box proper, in which the sand collects in the customary manner, and is cleaned out whenever the wheel is taken off for oiling, and 50 the inner groove, H, serves more particularly as a receptacle for the oil and axle-grease, and presents a more effectual bar to the entrance of sand to the wearing part of the axle. The amount of oil or grease which escapes around 55 the edge of the flange F agglutinates and holds the sand in that channel, so that very little passes through into the groove H, and what little may pass over is held there by the grease and does not reach the axle-bearing. 60

By means of my improvement the sand and dust that have heretofore found their way past the flange D are entirely excluded.

What I claim as my invention is—

The flange F, in combination with the axle 65 provided with the flanges D and E, and the axle-box B, closely surrounding said flanges, whereby the two inclosed grooves or channels G H are formed, substantially as described.

CHARLES COOK.
